UNITED STATES PATENT OFFICE.

AUGUSTUS C. L. DAVIS, OF MADISON, ASSIGNOR OF ONE-HALF TO AUGUST P. PILGER, OF NORFOLK, NEBRASKA.

FUEL-PRESS.

SPECIFICATION forming part of Letters Patent No. 247,891, dated October 4, 1881.

Application filed July 7, 1881. (No model.)

To all whom it may concern:

Be it known that I, AUGUSTUS C. L. DAVIS, of Madison, in the county of Madison and State of Nebraska, have invented a certain 5 new and useful Improvement in Fuel-Presses, of which the following is a specification.

This invention relates to a device for bundling fuel, such as cornstalks, hay, dry weeds, &c.

10 The invention consists in the construction of parts, as set forth hereinafter and claimed.

In the drawings, Figure 1 is a perspective view of the machine with a bunch of fuel compressed upon it. Fig. 2 is a perspective view 15 of one of the slats with the two parts of the constricting-cords passing through it.

A is the frame or table, supported on legs B, which are preferably pivoted to the frame at b, so that when the rods or braces are disconnected the legs may be turned up against the ends of the frame or table A, to render the machine more compact for shipping or storing. The two front legs may be connected by longitudinal brace D, and the two rear legs connected together in like manner.

25 E is a windlass-roller, from which project pins or studs e. The gudgeons (or shaft) of the windlass have journal-bearing in the ends of the frame A.

30 a are pins projecting from the front of the frame or table.

A' are rails or boards for the support of the material and the slats f, upon which it is laid. The slats form a compression-jacket to the material as it is compressed into cylindrical form 35 by the constricting-ropes F. The ropes F preferably pass through the slats, as shown most clearly in Fig. 2, so that they can be placed nearer together or farther asunder on the 40 cords. Two cords are shown, each of which is bent at the front part, f², where it passes around the studs or pins a, and the ends are secured to the bar f' by passing through the bar and being knotted at the ends, (or other 45 means of attachment may be made.)

The operation is as follows, (the frame standing upright on the legs, as shown:) The ropes are first laid on the table or frame with the loops f² (shown in the drawings on pins a)

upon the pins e and the bar f' hanging down 50 in front of the machine. The slats are strung along the cords at a proper distance asunder, and serve to keep the parts of the cord in the proper relative position. The material to be buunched is then laid upon the slats and cords, 55 (supported on the rails A.) Then the bar f' is carried over backward and put over the pins e, and the loops f² disconnected from the pins e and engaged on the pins a, in front of the machine. The windlass is now turned by means 60 of its crank E' until the fuel is pressed sufficiently tight; or the final pressure may be brought upon it by means of the hand bar or spike G. The pawl E², engaging with a suitable ratchet, E³, on the windlass, acts to prevent the loosening of the cords by holding the windlass in any position to which it may have been brought by the hand-crank or hand-bar. The roll of fuel is bound by wire or other ties H. The windlass may then be released from 65 the pawl by throwing the latter back from the ratchet-wheel E³ upon the windlass-shaft, and the ropes removed from the roll of fuel, which may then be sawed up into lengths.

Having thus described my invention, the following is what I claim as new and desire to secure by Letters Patent:

1. The combination of frame A A', windlass E, studs a a on the frame, studs e e on the windlass, ropes F, connected with studs a a at 80 one end, bar f', secured to the outer ends of the ropes and engaging with the studs on the windlass, and a suitable handle for turning the windlass, as set forth.

2. The fuel-press consisting of frame A, pivoted legs B, bracing C, windlass E, handle E', ratchet-wheel E³, pawl E², studs a and e, ropes F, and bar or rod f', substantially as set forth.

3. The fuel-press consisting of the frame A, pivoted legs B, braces C, windlass E, crank-handle E', pawl E², ratchet-wheel E³, studs a and e, and ropes F, having slats f mounted thereon, as set forth.

AUGUSTUS C. L. DAVIS.
